(57) **CLAIM**

The ornamental design for a motor vehicle, as shown and described.

DESCRIPTION

FIG. 1 is a left elevational view of a motor vehicle according to the present invention showing the present design;

FIG. 2 is a right elevational view of a motor vehicle according to the present invention showing the present design, the right elevational view thereof being a mirror image;

FIG. 3 is a top plan view thereof;

FIG. 4 is a rear elevational view thereof;

FIG. 5 is a front elevational view thereof;

FIG. 6 is a perspective view of the front and left side thereof;

FIG. 7 is a perspective view of the back and left side thereof;

FIG. 8 is a perspective view of the front and left side of the motor vehicle of FIG. 6. In the present design, shown for illustrative purposes and not forming part of the claimed design, transparent parts are shown with oblique lines and translucent parts are shown with crosshatched lines; and, FIG. 9 is a perspective view of the back and left side of the motor vehicle of FIG. 7. In the present design, shown for illustrative purposes and not forming part of the claimed design, transparent parts are shown with oblique lines and translucent parts are shown with crosshatched lines.
